(57) **CLAIM**

The ornamental design for a log handling tool, as shown and described.

DESCRIPTION

FIG. 1 is a front right perspective view of a log handling tool;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top view thereof;
FIG. 7 is a bottom view thereof;
FIG. 8 is an exploded front right perspective view thereof; and,
FIG. 9 is a right side elevation view showing a log handling tool positioned on the ground, shown in a state of use. The broken lines showing of the ground in FIG. 9 illustrates the environment of the claimed design and forms no part thereof. The remaining broken lines in the drawings illustrate portions of the log handling tool and form no part of the claimed design.

1 Claim, 8 Drawing Sheets
